United States Patent Office.

HENRY SHLAUDEMAN, OF DECATUR, ILLINOIS.

Letters Patent No. 77,664, dated May 5, 1868.

IMPROVED BEER-COOLER.

The Schedule referred to in these Letters Patent and making part of the same.

TO ALL WHOM IT MAY CONCERN:

Be it known that I, HENRY SHLAUDEMAN, of Decatur, county of Macon, and State of Illinois, have invented certain new and useful Improvements in Beer or Liquor-Coolers; and I do hereby declare that the following is a full, clear, and exact description of the same, reference being had to the accompanying drawing, and the letters of reference marked thereon, making part of this specification, in which—

Figure 1 is a plan view.

Figure 2 is an end sectional view.

Figure 3 is a top view, showing the arrangement of the troughs.

Figure 4 is a modification, showing the pyramidal form, the side plates being plain instead of corrugated, as shown in fig. 2.

Figure 5; the distributing-trough.

I am aware that beer-coolers have been used in which the beer was caused to pass over a series of tubes. I am also aware that corrugated plates of metal have been used, in which the plates were placed perfectly parallel to each other, thereby forming, as it were, a series of tubed plates, the water passing through the corrugations precisely on the same principle as when independent tubes have been used.

My invention differs entirely from that class of inventions for cooling beer or other liquor, where a series of independent tubes were used, as well as the corrugated plates, when the same were so placed as to form a series of tubes permanent in themselves, the corrugated edges being brought to bear so as to form a series of water-tight tubes. In all the "coolers" based on either of these theories, the water for the purpose of cooling the beer is caused to pass from the lower tube to the next upper one, and so on through the entire series.

My invention consists in forming a pyramidal cooler of two corrugated plates of metal, when the same is so constructed as to form an angle at the point where the beer is discharged from the trough, and at the same time is provided with a base of sufficient width as to enable the cooler to stand without the introduction of any frame for the purpose of supporting the same.

The great advantage of this construction will readily suggest itself to any one who is familiar with the class of inventions to which mine belongs. In the first place, ready access can at all times be had for the purpose of cleansing the cooler, not only to its sides, but also to its base. This pyramidal-formed cooler I place in a trough formed of a corrugated plate of metal, resting on a plain surface. This trough is so constructed as to readily admit of the free entrance of a continuous stream or current of fresh water, the water, by means of suitable connections, being introduced into the pyramidal-formed cooler from the trough, gradually ascending therein, not through a series of tubes, but being caused to traverse and pass over the inner surface of the corrugated plates unobstructed. The warm water passes out by means of a jet-pipe or discharge, near the angular connection of the side-plates of the cooler. The end-connecting plates are so-constructed as to extend a short distance above the angular connection of the pyramidal form, and are provided with projecting lips or bearing-flanges, which furnish the necessary supports for the troughs. These troughs are provided with suitable slots or loops, passing over the bearing-lip or flange referred to, whereby the same is held in position.

The great advantage of my improvement consists simply in this, that I eschew, entirely, what is commonly known as the "trickling" process. The great desideratum at which I aim, and which I attain, is a continuous flow when the same is caused to pass over an extent of cooling-surface unattainable in any other device, and especially where the heated beer is caused to traverse over parallel plates or corrugated tubes, when the same are so arranged as to form, as it were, a series of tubes.

To enable others skilled in the art to make and use my invention, I will now proceed to describe its construction and operation.

A is the trough; constructed with suitable frame-sides, *a. a.* In this trough I place one or more corrugated or plain plates, A'. In the upper plate, I insert two projecting couplings or tube-connections; B and B'. The tube-connection B is the one through which the cold water is admitted to the trough. It will be observed, by

reference to fig. 2, that the current or stream of water introduced at B, is, by means of the corrugated plate A', caused to traverse, not only the entire base of the trough, but also the whole extent of the convexed surface presented by the corrugated plate or plates A'. In this trough I place the pyramidal-formed cooler C, which is formed of two corrugated plates, C' C', or the surface of these plates may be plain, as shown in fig. 4. These plates may be made of copper, galvanized iron, or any other suitable material, and are united at their to a plain or corrugated plate, c. The plates C' C' may be struck up with suitable flanges, by means of which the base, c, can readily be riveted or soldered to the side-plates C' C'. Between these plates C' C', I insert a series of brace-rods, c' c'. The ends of these plates are united by suitable angular plates, D D, the same being provided, at their upper end, with bearing-flanges d d, over which pass suitable loops or other connections, attached to the end of the distributing-trough. These plates may be provided with a suitable man-head, by means of which ready access may be had to the interior of the chamber C. These end-plates D D are provided with two coupling-hose mouths, d' d'. The coupling-mouth d', by means of suitable hose or pipe, is firmly united with the coupling-opening B'. The upper opening, d', in the opposite plate, D, is for the escape of the warm water, heated by the action of the beer as it passes over the sides C' C'. E and F are two troughs, the trough F being constructed with numerous perforations, so as to act upon the well-known principle of the sieve. The lower trough, E, is provided with suitable discharge-openings, so arranged as to distribute the beer received from the trough F equally on both sides of the pyramidal cooler C. G is a distributing-pipe, in communication, by means of suitable pipes, g, with the kettle or other hopper from which the warm beer is received.

The operation is as follows: Water is introduced by means of the pipe B from any suitable vat, or by means of a force-pump, or other equivalent device. This water is caused to traverse not only the entire surface of the base of the trough A, but the inner surface of the corrugated or plain plate A'. This water is then communicated to the pipe or opening d' by means of a suitable hose or connection, B'. The whole volume of water is thereby thrown into the open chamber, formed by means of the plates C' C' of the pyramidal cooler C. As the water becomes heated, it passes out or is discharged, by means of the upper mouth or opening, d', in the upper-angular face-plate-D. The beer to be supplied to the cooler is received through the pipe g from the kettle, or other vessel, and, by means of the perforated pipe G, is discharged into the sieve-trough F, from whence it passes to the distributing-trough E, from whence, by means of suitable apertures or openings, it is equally distributed on the side-plates C' C' of the cooler C, when it flows to the trough, and is drawn off by means of the discharge-pipe H, after passing through the sieve H', thence to a fermenting-vat, which completes the operation of the cooler.

Having thus fully described the nature of my invention, what I claim therein as new, and desire to secure by Letters Patent of the United States, is—

1. The pyramidal cooler C, when the same is formed of either plain or corrugated sides C' C', and the whole is so constructed and arranged as to leave an open chamber for the reception of water, substantially as described.
2. I claim the independent base-trough A, when the same is constructed and arranged substantially as described, and for the purpose specified.
3. I claim the pyramidal cooler C, when the same is formed of either plain or corrugated sides C' C', and the whole is so constructed and arranged as to leave an open chamber for the reception of water, in combination with the base-trough, when the whole is constructed and arranged substantially as described, and for the purpose specified.

In testimony whereof, I have signed my name to this specification in the presence of two subscribing witnesses.

H. SHLAUDEMAN.
